[57] **CLAIM**

The ornamental design for a paint can handle positioning device, as shown and described.

DESCRIPTION

FIG. 1 is a front view of the invention;
FIG. 2 is a rear view of the invention — demonstrating areas of adhesive and removable adhesive protection;
FIG. 3 is a perspective view of the invention as used in application — demonstrating mode of attachment of invention to paint can;
FIG. 4 is a perspective view of the invention following application to paint can; and,
FIG. 5 is a perspective view of the side opposite that in FIG. 4.
The broken line showing of a paint can is for illustrative purposes only and forms on part of the claimed design.

FIG 1

FIG 2

FIG 3

FIG 4

FIG 5
